D. H. HARNLY

WEATHERPROOFING STRUCTURE

Filed Sept. 23. 1926

FIG. 1

FIG. 2

UNITED STATES PATENT OFFICE.

DAVID H. HARNLY, OF CHICAGO, ILLINOIS.

WEATHERPROOFING STRUCTURE.

Application filed September 23, 1926. Serial No. 137,200.

This invention relates to a weather proofing structure especially adapted for use in connection with windows but susceptible of use in other places.

- 6 In the past, rubber has been used in connection with windows, but has been found unsatisfactory in that it was more or less stiff and would not exclude the weather and dust.
- 10 According to this invention, felt or a similar flexible substance is used that will not only effectively exclude the weather, but that will also catch the dirt and dust, and that will not exert pressure against the window to interfere with its operation, in combination
- 15 with means for partially encasing the same and means for securing the partially encased strip in proper position.

The invention comprises the novel structure and combination of parts hereinafter described and more particularly pointed out and defined in the appended claims.

In the accompanying drawings which illustrate a preferred embodiment of this invention and in which similar reference numerals refer to similar features in the different views:

Figure 1 is an enlarged sectional view through a window equipped with a weather proof structure involving this invention.

30 Figure 2 is an enlarged sectional view upon the line II-II of Figure 1.

Figure 3 is a fragmentary view similar to Figure 2 illustrating a slight modification of the invention.

35 In its broadest aspect, this invention comprises a partially encased weather strip of felt or the like and a holding attachment therefor provided with a lodgment or separable parts for securing the encased portion

40 rable parts for securing the encased portion of the weather strip for ready application to the window or structure where it is to be used. The structure to which it is applied usually consists of a stationary part and a movable part. The holding attachment to-

45 together with the weather strip is usually applied to one part and a groove is formed in the other part for receiving the unencased portion of the weather strip which is usually made of felt or the like, and the resulting structure is such that the movable part may 50 always be readily operated with ease.

In the drawing, the invention has been il-

lustrated as applied to a window, and there is shown a section through a window of a pull-man car. The window pane 1 is confined in the usual frame comprising the upper rail 2, the lower rail 3, and the stiles 4, only one of which is shown. The stiles are slidably mounted in the grooves 5 in the sides of the window frame 6 as is common in the art. A groove or way is formed in connection with each stile of the window, either upon the inner or outer side thereof, depending upon the particular case. In Figures 1 and 2, a groove or way 7 is shown as formed in one side of the stiles 4 while in Figure 3, an angle member 8 is secured to the window stile at a suitable distance from the side of the window frame 6 to provide a groove or way 7^a. This latter construction is preferably used where metal window frames are used. The groove or way 7 or 7^a is co-extensive with the opening for the sliding window as shown in Figure 1.

A felt strip 9 or the like is confined or partially encased in the fold of a metal clamp 10 which is formed by bending a suitable strip of metal upon itself. One margin of the felt is inserted in such fold which is preferably made sufficiently wide to enclose substantially half width of the felt strip. The upper 80
ply of the fold is preferably indented along a line 11 for a purpose that will later appear. The 75

The thuswise partially encased weather strip is secured in a holding attachment which consists of separable parts or members 12 and 13, which are in the form of plates and which are so formed as to provide a lodgment therebetween for receiving and securing the encased portion of the weather strip. Thus the plate 13 is provided with an offset margin which takes over the rear part of the fold 10, and a downwardly curved edge 14 which engages the indented line 11 of the fold to secure the encased weather strip between said separable parts or the lodgment therebetween. This holding attachment with the partially encased weather strip may be applied as a unit or as separable parts to the desired window or the like. The plates 12 and 13 are screwed or fastened to the sides of the window frame so that the free and unencased part of the felt strip projects into the groove or way 7 or 7a.

It will be appreciated that this structure

will allow sufficient flexibility so as not to interfere with the operation of the window, and at the same time, the weather, dirt and dust will be effectively excluded on account of 5 the circuitous path occasioned by the groove or way. It will be readily apparent that the dirt or dust will tend to become lodged in the felt and that it cannot go any further.

In Figures 2 and 3, this weather proofing 10 structure is shown applied to the sides of a window. It may also be applied to the bottom thereof as shown in Figure 1. In such a case, the window sill is provided with a way or groove 7^b which is formed in the sill. When 15 the window is closed, the free margin of the felt will fit in this groove and exclude the weather.

While I have illustrated my improved 20 weather proofing structure in connection with a window, it should be understood that it is not limited to such use but may be used wherever the same may be applicable.

I am aware that many changes may be made, and numerous details of construction 25 may be varied through a wide range without departing from the principles of this invention, and I therefore do not purpose limiting

the patent granted hereon, otherwise than necessitated by the prior art.

I claim as my invention:

1. A weather strip comprising a flexible member, a metal sheath partially incasing the same, a base support for said incased member, and a metal plate secured at one edge to said base support and having a deformed part extending over said incased member, said deformed part terminating in a gripping edge for engaging said sheathed member and anchoring the same to said base support. 30

2. The combination with a window frame, 40 of a window having stiles slidable in said frame, said stiles having grooves, a partially incased weather strip having its unincased portion extending into one of said grooves and positioned against the window frame, 45 and an anchor plate secured to said window frame and having a deformed portion extending over the incased part of said weather strip, said deformed part terminating in a gripping edge for engaging said weather strip. 50

In testimony whereof I have hereunto subscribed my name.

DAVID H. HARNLY.
